(57) **CLAIM**

The ornamental design for a bingo card support board, as shown and described.

DESCRIPTION

FIG. 1 is a perspective view of a bingo card support board.
FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is a perspective view of the bingo card support board in full lines with a bingo card shown representing environmental association matter being for illustrative purposes only and forming no part of the claimed invention.
